UNITED STATES PATENT OFFICE

115,404

DESIGN FOR A DISPLAY STAND

Ota O. Hobson, Chariton, Iowa

Application July 18, 1938, Serial No. 78,569

Term of patent 3½ years

To all whom it may concern:

Be it known that I, Ota O. Hobson, a citizen of the United States, resident of Chariton, Lucas County, Iowa, have invented a new, original, and ornamental Design for a Display Stand, of which the following is a specification, reference being had to the accompanying drawing, forming a part thereof.

Fig. 1 is a top plan view of the article, showing my design; and

Fig. 2 is a front perspective view thereof, the perforation being continued throughout the portions shown plain.

I claim:

The ornamental design for a display stand, substantially as shown and described.

OTA O. HOBSON.
